Inventor:
Siegmond Loewe

UNITED STATES PATENT OFFICE

SIEGMUND LOEWE, OF BERLIN, GERMANY, ASSIGNOR TO RADIO CORPORATION OF AMERICA, A CORPORATION OF DELAWARE

MULTIPLE-GRID THERMIONIC TUBE

Application filed July 27, 1926, Serial No. 125,312, and in Germany August 1, 1925.

This invention relates to a thermionic tube having a plurality of grids, which may especially be used for so-called compensating connections, whereby sums or differences of electrical currents have to be formed.

Especially for connections serving for the suppression of disturbances it is necessary to form the electrical difference of two simultaneously occurring receiving actions, of which 10 for instance the one receiving action consists of the disturbances alone, and the other receiving action consists of the sum of the reception proper and the disturbances. A reception of this kind may, for instance, be obtained by two similar receiving sets, of which 15 one set is sharply tuned to the wave to be received, while the other set is adjusted for a wave which is slightly different from the former wave. In order to suppress the disturbances, it will only be necessary to form the 20 electrical difference between the two receiving actions.

The accompanying drawing shows dia- 25 grammatic representations of two forms of multiple grid tubes according to this invention, one form being shown in Fig. 1 and the other form in Fig. 2 in a view taken perpendicularly to the anode, grid and filament system. Fig. 3 is a section through the anode, 30 grid and filament system of Fig. 2.

In Fig. 1 the incandescent filament or cathode is designated by the numeral 1, while the numerals 2 and 3 refer to parallelly wound grids, which are insulated from each other. 35 The anode is designated by the numeral 4. The entire system is mounted within a glass-bulb 5 and comprises two leads 6 and 7 for the heating filament, two leads 8 and 9 for the grids and a lead 10 for the anode. In 40 practice the heating filament is preferably stretched out in a straight line between the two grids, and positioned as symmetrically as possible with regard to the latter, while the anode surrounds the entire system symmetrically. For practical connections the 45 tube is used in such a way, that the one receiving action is caused to play between the cathode and the one grid 2, and the other receiving action between the same cathode and the second grid 3. In this manner the sum

of the receiving actions will be obtained. In order to form the difference between the two receiving actions the phase of the one receiving action is displaced by 180°, or a tube 55 is interposed with reversed connections.

The tube as above described, may be improved in such a way, that the advantages of the double-grid tube may be utilized simultaneously. In Fig. 2 a tube of this kind is represented, having a space charging grid. 60 Fig. 2 also shows another construction of the compensating grid. The leads for the cathode are again designated by the numerals 6 and 7, while the leads for the two compensating grids are designated by the numerals 8 and 9. The space charging grid is represented at 11. The compensating grid consists of two grid systems, of which one is placed within the other. The one system is fastened to a ring 12 and the other system to a like ring 13. The bars of the combined grid system are distributed over a cylinder surface in such a manner that alternately a bar of one grid system is connected to the ring 12, and a bar of the other system to the ring 13. Within the space, which is surrounded by the combined system of the grid bars, there is placed the straight incandescent cathode 1, the space charging grid 11, and in addition thereto the concentrically arranged anode 4. In Fig. 3, 75 which is a cross-section through Fig. 2 the glass-bulb is represented at 14. The cylindrical anode is shown at 4 and the rings at 13. These rings carry alternately the grid bars, which are connected to the same. 80 11 is the space charging grid, which is formed, for instance, by a spiral, said spiral appearing in its projection as a circle, the point 1 in the centre representing the straight cathode 90 as seen in its projection. In a compensating grid tube of this kind having a protective screen, the interior grid 11 would have to be omitted and substituted by a screen placed between the rings 12 and 13 and the anode 4. 95

In many cases of connections, the special space charging grid or anode protecting screen grid may be dispensed with, and one or both compensating grids may be used simultaneously for this purpose. 100

I claim:

1. A multiple grid thermionic tube, comprising a plurality of grids adapted to exert the same tube controlling action, an anode positioned concentrically with respect to said grids, and an additional grid adapted to act as a space charging grid or protective screen for said anode.
2. A multiple grid thermionic tube, comprising two grids which are insulated from each other and adapted to exert the same tube controlling action, each of said grids consisting of a ring with grid bars fastened perpendicularly thereon, said rings and grid bars of each grid being positioned relatively to each other to form a combined cylindrical grid system having grid bars which alternately belong to the one and the other grid, a filament placed essentially in the direction of the axis of said combined cylindrical grid systems, an anode concentrically mounted with respect to the combined grid system, and a third grid adapted to act as a space charging grid or protecting screen for said anode.

In testimony whereof I have affixed my signature.

SIEGMUND LOEWE.
